UNITED STATES PATENT OFFICE.

THOMAS N. PATRICK, OF NEW YORK, N. Y.

CAMPAIGN TOY.

SPECIFICATION forming part of Letters Patent No. 581,302, dated April 27, 1897.

Application filed November 6, 1896. Serial No. 611,228. (No model.)

To all whom it may concern:

Be it known that I, THOMAS N. PATRICK, a citizen of the United States, residing at New York, in the county of New York and State 5 of New York, have invented certain new and useful Improvements in Campaign Toys; and I do hereby declare the following to be a full, clear, and exact description of the invention, such as will enable others skilled in the art to 10 to which it appertains to make and use the same.

My invention relates to improvements in toys, the prime object of the same being to provide a campaign toy which will afford amusement to both old and young in determining at different times "who is on top" in 15 the political arena.

The invention consists of a rubber ball having two circular openings therein at diametrically opposite points, tubes fitting within 20 said openings, a shaft projecting through the bottoms of said tubes, a stop for limiting the outward movements of said shaft, suitable heads of candidates or others connected to the outer ends of said shaft, and caps upon said 25 heads which are adapted to close the openings in said ball. I also provide upon the outer surface of said ball, adjacent to the openings therein, annular ledges or ridges, forming a double trackway upon which the ball 30 may be rolled.

The invention also consists in other details of construction and combinations of parts, which will be hereinafter more fully described and claimed.

35 In the drawings forming part of this specification, Figure 1 represents a view of the outer surface of my improved toy with one of the heads projecting outwardly therefrom. Fig. 2 is a longitudinal sectional view through 40 the same. Fig. 3 is a perspective view of one of the tubes fitting within said ball.

Like reference-numerals indicate like parts in the different views.

The ball 1 is preferably constructed of rubber, although it may be made of any suitable material. The same is provided with circular openings 2 3 at diametrically opposite points, in which openings fit the tubes 4 5, which project inwardly toward the center of 45 the ball 1. Said tubes are formed with annular flanges 6 at their outer ends, which are adapted to fit upon the outer surface of the

ball 1, adjacent to the openings therein, forming the means whereby the tubes may be sewed, riveted, or glued in place. Each of 55 the tubes 4 5 has a bottom 7, through which projects a shaft 8, having a stop or shoulder 9, secured to or formed integral therewith, for limiting the outward movements of said shaft by its engagement with the inner end of one 60 or the other of said tubes. Secured in any suitable manner to the outer ends of the shaft 8 are rubber or wooden heads 10 11, representing candidates for office, as "Bryan" and "McKinley," or, if desired, an ornamental 65 head or head in caricature may be substituted therefor. The heads 10 11 have secured to them caps 12 12, which are adapted to fit within the openings 2 3 in the ball 1, according to the position to which the shaft 8 is shifted. 70 On the outer surface of the ball 1 I arrange two parallel ridges or ledges 13 13, which form a double trackway upon which the ball may be rolled.

When the device is used as a campaign toy, 75 the heads representing those of McKinley and Bryan may be secured to the outer ends of the shaft 8, and the object of it will be to determine which candidate is "on top" at any particular time. This is done by placing the 80 ball upon the floor or other flat surface and rolling it upon the trackway 13 13. At one minute the head of McKinley will project out through the opening 2, and at the next minute the head of Bryan will project out through 85 the opening 3. When the ball stops rolling, the one whose head is projecting will be the candidate whose chances appear to be the best at that time.

Instead of the representation of McKinley 90 and Bryan I may substitute any fanciful head or head in caricature and use the device for advertising purposes. I propose to ornament the outside of the ball with the representation thereon of two American flags, with nineteen 95 stars on each side thereof and seven stars above and between said flags, representing the number of States in the Union. This, however, is a mere detail and may be varied as convenience may dictate.

Having now described my invention, what I claim as new, and desire to secure by Letters Patent, is—

1. In a toy, the combination with a ball

having openings therein at diametrically opposite points, of a slidingly-mounted shaft containing the head of a man at each end thereof, one of which heads is adapted to be projected at a time through one or the other of said openings.

2. In a toy, the combination with a ball having circular openings therein at diametrically opposite points, of tubes fitting within said openings, a slidingly-mounted shaft connecting said tubes, and the head of a man upon each end of said shaft adapted to fit within said tubes and to be projected through the openings in said ball, substantially as and for the purpose described.

3. In a toy, the combination with a ball having circular openings therein at diametrically opposite points, of tubes fitting within said openings, a slidingly-mounted shaft connecting said tubes, a stop for limiting the outward movements of said shaft, and the head of a man upon each end of said shaft adapted to fit within said tubes and to be projected through the openings in said ball, substantially as and for the purpose described.

4. In a toy, the combination with a ball having circular openings therein at diametrically opposite points, and a pair of parallel annular ridges upon its outer surface forming a trackway upon which said ball may be rolled, of tubes fitting within said openings having annular flanges at their outer ends by means of which they may be secured to said ball adjacent to said openings, a slidingly-

mounted shaft connecting said tubes, a stop for limiting the outward movements of said shaft, and the head of a man upon each end of said shaft adapted to fit within said tubes and to be projected outwardly from the openings in said ball, substantially as and for the purpose described.

5. In a toy, the combination with a ball having circular openings therein at diametrically opposite points, and a pair of parallel annular ridges upon its outer surface forming a trackway upon which said ball may be rolled, of tubes fitting within said openings having annular flanges at their outer ends by means of which they may be secured to said ball adjacent to said openings, a slidingly-mounted shaft connecting said tubes, a stop for limiting the outward movements of said shaft, the head of a man upon each end of said shaft adapted to fit within said tubes and to be projected outwardly from the openings in said ball, and a cap upon each of said heads adapted to close the opening in said ball in which the head to which it is connected fits, substantially as and for the purpose described.

In testimony whereof I have signed this specification in the presence of two subscribing witnesses.

THOMAS N. PATRICK.
